PILE FABRIC AND METHOD OF MAKING
SAME

Horace Mellor, Sanford, Maine, assignor to Sanford Mills, Sanford, Maine, a corporation of Maine

Application November 3, 1936, Serial No. 108,937

8 Claims. (Cl. 139—397)

This invention relates to a cut warp pile fabric of that type in which the pile surface is formed by warp yarns concatenated with the weft or filling yarns so as to present sections having the general appearance of a W.

The object of the invention is to provide with such type of fabric a peculiar and distinctive striped effect with the stripes extending longitudinally of the fabric and in which the contrast between the stripes is effected by the concatenation of the yarns in the fabric. Thus the contrast is due to the way in which the yarns are concatenated and is entirely independent of the shade or color of the fabric.

15 The object of the invention is further to present in this type of fabric the contrasting longitudinal stripes by a construction and a method of construction of the fabric in which tufts of the pile in one set of stripes are inclined toward the ground in one general longitudinal direction and tufts of the pile in the other set of stripes are inclined toward the ground in the general opposite longitudinal direction. Thus the contrasting effect of the stripes is due to this difference in inclination as a result of which the light is absorbed and broken up in one set of stripes in a different way from the other so that to the observer a distinct contrast appears.

20 The object of the invention is further to provide such a fabric having the required contrasting longitudinal stripes which may be woven double, that is, with two pieces woven face to face and cut apart in the usual way.

25 The nature and objects of the invention will appear more fully from the accompanying description and drawing and will be particularly pointed out in the claims.

30 The drawing represents in an exaggerated and diagrammatic form a preferred construction of fabric embodying the invention and illustrative of the principles thereof and also of the steps of the method employed in the weaving of the same when the fabric is woven double.

35 In the drawing:

40 Fig. 1 is a perspective view of a small section of one of the fabrics.

45 Figs. 2, 3, 4, and 5 are diagrams illustrating vertical sections of the double fabric with these sections representing the yarns in successive dents in weaving the form of the invention illustrated in Fig. 1.

50 Fig. 6 is a top plan view of a small section of the fabric entirely diagrammatic to illustrate the effect of the contrasting stripes.

55 Fig. 7 is a view similar to Fig. 6 on a larger

scale illustrating the direction in which the tufts of the pile lie in the form illustrated and in two contrasting stripes.

As the general method of weaving a cut warp pile fabric in a double loom is well known to those skilled in the art, it is only necessary herein to illustrate and describe those features of the construction of the fabric and the method of weaving with which the present invention is particularly concerned and which enable the contrasting striped effect of the invention to be secured.

The diagrams in Figs. 2, 3, 4, and 5 represent a portion of the yarns with the warp yarns as they extend through successive adjacent dents of the loom and the lower fabric of which is separately illustrated in Fig. 1.

The successive picks of filling in the lower fabric are indicated at 1 to 12 and those in the upper fabric at 13 to 18. The ground warp yarns forming the back or ground of the lower fabric in the first dent are 19 and 20, in the second dent 21 and 22, in the third dent 23 and 24, and in the fourth dent 25 and 26, while the ground warp yarns of the upper fabric are similarly but reversely arranged as illustrated. There is shown at 27, 28, 29, and 30 a single pile warp yarn for each dent weaving back and forth between the two fabrics in the usual manner and extending between the ground warp yarns in each dent so that these pile yarns when cut apart form oppositely disposed W's in the two fabrics with the two fabrics when cut apart having the same concatenation of yarns.

It is understood, of course, that the construction is repeated both laterally and longitudinally and that only a small section is here illustrated. In the illustration the yarns shown in the first and second dents form a portion of one stripe and the construction in the third and fourth dents form a portion of a contrasting adjacent stripe. The width and number of the stripes will vary as required to produce the desired effect.

In the lower fabric illustrated separately in Fig. 1, there is shown in the first dent a series of W's formed by the pile yarn 27, in the second dent a series formed by the pile yarn 28, in the third a series formed by the pile yarn 29, and in the fourth a series formed by the pile yarn 30.

The contrast is effected by causing tufts such as the tufts or arms 31 of the pile W's in one set of stripes such as the stripe illustrated by the weave of the first and second dents to be inclined toward the ground in one longitudinal direction and by causing tufts such as the tufts or arms 55

32 of the pile W's in the other set of stripes such as the stripe illustrated by the weave of the third and fourth dents to be inclined toward the ground in the opposite longitudinal direction.

5 In the weaving of the fabric, the concatenation illustrated is effected in one set of stripes such as that represented by the first and second dents by causing the pile warp yarns or ends where the beginning of each W extends from the 10 ground to pass under the succeeding pick and with the ground warp end at one side thereof to pass over the said pick and with a plurality, preferably three, successive ground warp ends at the 15 other side thereof to pass under said pick while in the other set of stripes such as that represented by the third and fourth dents by causing the pile warp yarns or ends where the end or rear of each W extends from the ground to pass under the previous pick and with the ground 20 warp end at one side thereof to pass over the said pick and with a plurality, preferably three, successive ground warp ends at the other side thereof to pass under said pick. For example, referring to the construction of the lower fabric 25 and assuming that the pick 1 has been inserted and beaten in, the pile yarn which forms the beginning or tuft 31 of the first W in the first dent is lowered so that it will pass under the succeeding pick 2 while the ground warp end 19 at 30 one side of the pile warp is raised to pass over the pick 2 and the three successive ground warp ends 20, 21, and 22 at the other side of the pile warp 27 are lowered to pass under the pick 2. The same relative arrangement of yarns, it will 35 be seen, takes place at each tuft 31 forming the beginning of the W's in the stripe illustrated by the first and second dents. On the other hand, in the contrasting stripe illustrated by the third and fourth dents, it will be seen, assuming, for 40 example, that pick 6 has been laid and beaten in and the rear end 32 of the first W in the third dent has been formed, that the pile warp forming the end 32 extends from the ground at the rear of the W and passes under the previous pick 45 6 while the ground warp end 23 at one side passes over the pick 6 and the three successive ground warp ends 24, 25, and 26 at the other side pass under the pick 6. Without repeating, it will be 50 seen that the same relative concatenation is true of each W throughout the respective stripes of the fabric.

The result of this concatenation is that as the picks are beaten in the tufts of the W's in the stripe illustrated by the first and second dents 55 in Fig. 1 are forced toward the left end of the fabric and also toward the near edge; in fact, with the particular arrangement illustrated, the result is that each tuft 31 is forced down so as to be inclined toward the fabric and both toward 60 the left end of the fabric and toward the nearer edge. The rear tufts of the W's in this set of stripes is concatenated in the usual manner and stand relatively straight. In the contrasting set of stripes represented by the third and fourth 65 dents, as the fabric is beaten up, the rear tufts 32 of each W are caused to incline toward the right-hand end of the fabric but also toward the nearer edge and also to be well inclined toward the ground. This is due in both cases to 70 the fact that at one side of each W and at the end of each W, as required by the stripe, the ground warp end at one side weaves opposite to the pile warp while a plurality, preferably three, successive ground warp ends at the other 75 side weave with the pile warp.

When the fabric is beaten up and finished, the tufts forming the beginning of the W's in one set of stripes, woven as illustrated by the first and second dents of Fig. 1, extend in a direction inclined close to the ground in the direction of the left-hand end of the fabric and toward the near edge of the fabric, while the rear ends of these W's extend upward in the usual manner and are comparatively short. In the contrasting stripes represented by the construction of the third and fourth dents, the tufts forming the rear of each W extend in a direction inclined close to the ground in the direction of the right-hand end of the fabric and toward the near edge of the fabric, while the beginning ends of these W's extend upward in the usual manner and are comparatively short.

The result is to give a marked contrast between adjacent stripes and a contrast which is effected by the concatenation of the yarns in the fabric 20 so that the contrast is due to construction and exists even if the fabric be dyed entirely of the same shade.

In Fig. 6 a portion of a fabric is illustrated diagrammatically in which there are four stripes 25 33, 34, 35, and 36, each made up of five rows of pile with the tufts in the several rows inclined toward the ground and in the general direction indicated by the arrows at the top of the figure, while in Fig. 7 a similar diagrammatic view on a 30 larger scale is shown of a portion of the stripes 33 and 34 and with the tufts 31 and 32 and their direction indicated by the arrows.

While each tuft of pile is of the W type because of the manner in which it is concatenated with the successive picks of filling, it is very much distorted when the fabric is beaten up closely and if as a result there is any tendency of the pile tufts to work or push out of the ground, this is overcome by giving a light coating of 40 adhesive such as pyroxylin or rubber to the back of the ground of the type now commonly employed in connection with loosely woven pile fabrics of the V type.

The invention produces a fabric of a most 45 pleasing contrasting effect and one in which a great variety of contrast may be obtained by varying the relative widths of the stripes.

Having thus described the invention, what is claimed as new, and desired to be secured by 50 Letters Patent, is:

1. A cut warp pile fabric of the W type presenting contrasting longitudinal stripes in which the contrast is effected by the concatenation of the yarns of the fabric in which in one set of stripes the tuft at one end of each pile W and in the other set of stripes the tuft at the other end of each pile W extends upward from beneath a pick of filling and has at one side a ground warp yarn passing over the said pick and at the other side three successive ground warp yarns passing under the said pick with the result that the said tufts are held inclined toward the ground in a direction away from their respective W's and in both sets toward the said other side of the fabric. 65

2. A cut warp pile fabric of the W type presenting contrasting longitudinal stripes in which the contrast is effected by the concatenation of the yarns of the fabric in which in one set of stripes the tuft at one end of each pile W and in the other set of stripes the tuft at the other end of each pile W extends upward from beneath a pick of filling and has at one side a ground warp yarn passing over the said pick and at the other side a plurality of successive ground warp yarns 70 75

passing under the said pick with the result that the said tufts are held inclined toward the ground in a direction away from their respective W's and in both sets toward the said other side of the fabric.

5. 3. The method of forming a cut warp pile fabric of the W type to cause the fabric to present contrasting longitudinal stripes in which the contrast is effected by the concatenation of the yarns of the fabric which comprises weaving the fabric in one set of stripes with each pile warp end, where it extends from the ground at the beginning of each W, passing under the succeeding pick and with the ground warp end at one side thereof passing over said pick and with a plurality of successive ground warp ends at the other side thereof passing under said pick, and in the other set of stripes with each pile warp end, where it extends from the ground at the rear 10 of each W, passing under the previous pick and with the ground warp end at the one side passing over said pick and with a plurality of successive ground warp ends at the other side passing under said pick.

25. 4. The method of forming a cut warp pile fabric of the W type to cause the fabric to present contrasting longitudinal stripes in which the contrast is effected by the concatenation of the yarns of the fabric which comprises weaving the fabric in one set of stripes with each pile warp end, where it extends from the ground at the beginning of each W, passing under the succeeding pick and with the ground warp end at one side thereof passing over said pick and with three successive ground warp ends at the other side thereof passing under said pick, and in the other set of stripes with each pile warp end, where it extends from the ground at the rear of each W, passing under the previous pick and with the ground warp end at the one side passing over said pick and with three successive ground warp ends at the other side passing under said pick.

40. 5. The method of forming a cut warp pile fabric of the W type to cause the fabric to present contrasting longitudinal stripes in which the contrast is effected by the concatenation of the yarns of the fabric which comprises holding the pile warp end away from the back of the ground, and the ground warp end at one side thereof 45 away from the face of the ground, and the three

successive ground warp ends at the other side thereof away from the back of the ground each time a pick is inserted to hold the beginning end of each pile W in one set of stripes and each time a pick is inserted to hold the rear end of each pile W in the other set of stripes.

5. 6. The method of forming a cut warp pile fabric of the W type to cause the fabric to present contrasting longitudinal stripes in which the contrast is effected by the concatenation of 10 the yarns of the fabric which comprises holding the pile warp end away from the back of the ground, and the ground warp end at one side thereof away from the face of the ground, and a plurality of successive ground warp ends at the 15 other side thereof away from the back of the ground each time a pick is inserted to hold the beginning end of each pile W in one set of stripes and each time a pick is inserted to hold the rear end of each pile W in the other set of 20 stripes.

7. A cut warp pile fabric of the W type presenting contrasting longitudinal stripes in which the contrast is effected by the concatenation of 25 the yarns of the fabric and in which in one set of stripes the tuft of each pile W which is nearer one end of the fabric projects from beneath a pick of filling under which the adjacent ground warp at one side passes and over which the adjacent ground warp at the other side 30 passes and in which in the other set of stripes the tuft of each pile W which is nearer the other end of the fabric projects from beneath a pick of filling over which the adjacent ground warp at the said one side passes and under which 35 the adjacent ground warp at the said other side passes.

8. A cut warp pile fabric of the W type presenting contrasting longitudinal stripes in which the contrast is effected by the concatenation of the 40 yarns of the fabric and in which in one set of stripes the tuft of each pile W which is nearer one end of the fabric and in the other set of stripes the tuft of each pile W which is nearer the other end of the fabric projects from beneath a pick of filling over which the adjacent ground warp at one side passes and under which 45 the adjacent ground warp at the other side passes.

HORACE MELLOR. 50
